UNITED STATES PATENT OFFICE.

GUSTAV R. RODDY, OF MILWAUKEE, WISCONSIN, ASSIGNOR TO CHAIN BELT COMPANY, OF MILWAUKEE, WISCONSIN, A CORPORATION OF WISCONSIN.

LIQUID-SCREENING APPARATUS.

1,417,205.

Specification of Letters Patent. Patented May 23, 1922.

Application filed January 19, 1921. Serial No. 438,487.

To all whom it may concern:

Be it known that I, GUSTAV R. RODDY, a citizen of the United States, residing at Milwaukee, in the county of Milwaukee and State of Wisconsin, have invented certain new and useful Improvements in Liquid-Screening Apparatus, of which the following is a specification.

This invention relates to endless traveling water screens such as are employed to treat sewage, water taken from streams and used for industrial purposes, etc.

In the use of apparatus of this kind the water to be screened is usually taken through a channel comprising a chamber into which one end of the screen is inserted, while its upper end extends above the liquid level, that the material collected thereby may be the more easily removed. A common form of liquid screen consists of a series of perforated metal plates secured to endless chains and operated so that the upper, and upwardly moving, run thereof, is the one that performs the separating action. Such a screen is usually mounted in a rigid frame carrying the wheels with which the chains carrying the screening plates engage, and this is usually hinged, so that the frame may be let down into the screening chamber of the waterway or may be lifted therefrom when not in use or when requiring repairs.

When apparatus of this kind is in use, the water upon one side of the screen,—the side toward the intake of the conduit,—is fouled with the material the screen is intended to remove, while that on the other side, having passed through the screening surface, is cleansed of the material the screen removes; and in order that the separation between the screened and unscreened bodies of water may be maintained as perfect as possible, so as to insure that all the water that flows through the conduit shall pass through the screening surface, and not around the sides or ends thereof, various sealing means have been devised.

My invention relates to such sealing means.

In the accompanying drawings—
50 Figure 1 is a view, parts in longitudinal section and others in elevation, of a liquid

screening apparatus embodying my present improvements.

Fig. 2 is a transverse sectional view taken on the line II—II of Fig. 1 on a larger scale 55 than Fig. 1.

Fig. 3 is a longitudinal sectional view taken through the lower, immersed, end of the screen.

Fig. 4 is a transverse sectional view on the 60 line IV—IV of Fig. 3.

In the drawings A represents a frame, hinged at a, and in which operates an endless traveling liquid screen B. In the frame are mounted the wheels C on which are supported the screen and about which it turns. The parts thus far referred to may be of widely different specific construction, and therefore are not illustrated in detail. The free end of the frame A is adapted to be 70 lowered into a chamber D through which the liquid to be screened flows. This chamber is usually built of concrete, and is of a little greater width than the screen and its frame A. 75

The direction of movement of the screening surface is indicated by arrows, the uprun thereof being the working portion, and the body of the liquid above the line of the said uprun and toward the foot or free end 80 of the screen is the unscreened liquid, while that on the opposite side of the said uprun of the screen—below the plane of said run and toward the head of the frame,—is the body of cleansed liquid. 85

In order to form cut-offs separating these bodies of liquid, and located between the screen frame and the side walls of the chamber D, it has been proposed to secure to or set into the said chamber walls inwardly 90 projecting flanges 2 parallel with the working run of the screen, and to have engaged therewith, by overlaying them, other flanges that are secured to and projecting from the sides of the screen frame. 95

In installations of water screens of the type to which my invention is applied, it is common practice for the party who is to be the user of the screen to construct the chamber D and to set the flanges 2 in the 100 walls thereof, as the screen cannot be put into place until the concrete of which the

chamber walls are formed has hardened, and it is desirable to set the flanges 2 at the time the walls are constructed.

But much difficulty has been experienced when this practice has been followed, in getting the flanges on both sides the screen frame to accurately fit the flanges set in the walls of the chamber. The fit on one side may be accurate and all that is to be desired, while that upon the opposite side is not accurate and allows a space between the flanges, through which liquid passes unscreened. Various means have been resorted to to overcome the difficulties just suggested, such as not setting the wall flanges 2 until the time when the screen is installed, or supporting the screen frame flanges so that they may be adjusted, but these expedients are not entirely satisfactory.

In practicing my invention the wall flanges 2 are put in place when the wall is constructed, being set as nearly to the desired line as possible. Another set of flanges, 3, are secured to the sides of the screen frame, projecting laterally therefrom, and being located so that when the screen is installed and let down into the chamber D the flanges, 2 and 3, of each set will lie in the same inclined plane, edge to edge but separated from each other by a narrow space. This space is then covered by a separate sealing bar 4 adapted to rest upon the two flanges, and to cover and close the space between them. The bar is preferably of T-shape in cross section, and its central rib or flange 5 lies in the space between the bars 2 and 3. The flanges 3 are preferably secured to the screen frame at its upper edges, as represented in Fig. 2.

Eye bolts 6 may be fastened to the sealing bars into which hooks are inserted to facilitate handling the bars in placing and removing them. In place of eye bolts holes may be punched through the bars to receive a hook, but the eye bolts are preferred.

The advantages of the cut-off arrangement shown is its simplicity of construction, and effectiveness in closing the open spaces between the sides of the screen frame and the side walls of the chamber in which the screen operates, and its ability to adjust itself to slight variations in level that may exist between the wall and frame flanges, or differences in the width of the spaces between the edges of the opposing flanges due to inaccurate construction of the chamber walls, setting of the wall flanges 2, or inaccurate mounting of the supports for the screen.

In using water screening apparatus such as herein described it is customary to have the lower immersed end of the screen frame rest in a transverse recess or pocket formed therefor in the bottom of the chamber D,

such as indicated at F; and it is necessary that cut-off means, separating the bodies of unscreened and screened water, be provided at the said end of the screen. The recess or pocket F facilitates the construction and arrangement of the screen foot cut-off, means which constitute one of the features of my present invention.

The immersed end of the screen frame, —in which the lower sprocket wheels C are mounted, and where the screen makes the turn from the lower, down-moving run, to the upper, upward moving run—, is preferably closed in by transverse walls 7 the edges of the ends of which approach as closely as practical to the moving screen surfaces.

Secured to the screen frame A near its lower end are cut-off plates 8 to which are secured a cross bar 9. To the latter is united, by the hinge 10, a crosspiece 11, preferably of angular shape, with one member secured flatwise against the hinge and the other resting against the edges of the parts 8 and 9 so as to hold the crosspiece in proper normal position. A contact piece 12, formed preferably of wood, is supported by the crosspiece 11. This contact piece is shaped so that its free end 13 is adapted to rest upon the upwardly moving screen surface 95 and forms a liquid seal along the lines of its contact. It is adjustably supported, as by means of screw-threaded rods 14, 14, seated in the hinged crosspiece 11 where they are secured by nuts 15. The threaded portions of the rods 14 preferably have engagement with a metal plate 16 seated in the upper face of the contact piece 12.

A cut-off plate 17, hinged at 18 to the floor of the chamber D near the edge of the recess or pocket F, is adapted to rest upon the cut-off plates 8 and 9.

The cut-off plates 8 have close engagement with the transverse wall 7 for the lower immersed end of the screen, and, in connection with the hinged plate 17, prevent flow of unscreened water around the end of the screen frame. The cut-off piece 12 prevents the flow of unscreened water down the faces of the upwardly moving screening plates and so under the wall 7, by which path it might reach and become mixed with the body of screened liquid.

The cut-off parts here described for the lower end of the screen are all, with the exception of the plate 17, supported directly by the screen frame. The hinging of the plate 17 permits it to be moved back out of the way of the end of the screen when that is lifted from or lowered into the pocket F. By hinging the cut-off piece 12 it is permitted to move should any object caught by the screen come into engagement therewith and be carried past it. The adjustable manner of supporting the contact cut-off piece 130

12 permits it to be accurately set with reference to the moving screen surface.

Having described my invention what I claim is:—

5 1. In a liquid screening apparatus comprising a chamber through which flows the liquid to be screened and a frame carrying the screen and adapted to be placed in the said chamber, cut-off means to separate the
 10 unscreened and the screened bodies of the liquid, located between the screen frame and the side walls of the chamber, and consisting of flanges secured to the said chamber walls and projecting toward the screen
 15 frame, and other flanges carried by the screen frame and arranged to lie opposite to the said wall flanges and in approximately the same plane, but separated therefrom by narrow open spaces, and separate
 20 cover plates resting on the said flanges and closing the open spaces between them.

2. Apparatus such as set forth in claim 1 when the cover plates are T-shaped and the central flanges thereof lie in the spaces between the wall and screen frame flanges.

3. Apparatus of the character stated in claim 1 wherein the screen carried by the frame is an endless traveling screen the uprun of which constitutes the working screening surface, and wherein the screen frame flanges of the cut-off are carried by the upper edges of the screen frame.

4. Apparatus of the character stated in claim 1, wherein the screen is an endless traveling one, having cut-off means for separating the unscreened from the screened liquid located at the immersed, foot end of

the screen, and consisting of a transverse cut-off extending across the uprun of the screen near its lower end and supported 40 from the screen frame.

5. Apparatus such as specified in claim 4 in which the transverse cut-off has a hinge support permitting it to yield to allow material that may be carried upward by the 45 screen to pass.

6. Apparatus such as specified in claim 4, in which the transverse cut-off is adjustable toward and from the screening surface.

7. Apparatus such as specified in claim 4, in which the transverse cut-off has a hinge support and is also adjustable toward and from the screening surface.

8. Screening apparatus such as stated in claim 1 wherein the screen is an endless 55 traveling one, having its lower immersed end enclosed by a transverse wall, and the chamber in which the screen operates having a recess in which the said immersed end of the screen is located, transverse cut-off 60 means for preventing the flow of unscreened liquid around the lower, immersed end of the screen, comprising a plate hinged to the bottom of the chamber, serving to cut off the flow of liquid around the immersed end 65 of the screen outside the said transverse inclosing wall, and a transverse cut-off carried by the screen frame and held in close engagement with the moving screen surface and serving to prevent flow of water around 70 the screen end inside the said transverse wall.

GUSTAV R. RODDY.
